United States Patent Office

Des. 229,187
Patented Nov. 13, 1973

229,187

ELECTRICAL INSULATOR OR SIMILAR ARTICLE

Edward A. Vrabel, Pittsfield, Mass., assignor to
General Electric Company

Filed Oct. 27, 1971, Ser. No. 193,241

Term of patent 14 years

Int. Cl. D13—03

U.S. Cl. D26—10

Fig. 1.

Fig. 2.

Fig. 3.

FIG. 1 is a side elevation view of an electrical insulator or similar article showing my new design, the opposite side being substantially a mirror image thereof;

FIG. 2 is an end elevation view, showing the bottom end thereof;

FIG. 3 is an end elevation view, showing the top end thereof.

I claim:

The ornamental design of an electrical insulator or similar article, as shown and described.
